UNITED STATES PATENT OFFICE

2,058,332

MACHINE FOR MAKING FILAMENT
SUPPORTING STRUCTURESFrank J. Malley, Cleveland Heights, Ohio, as-
signor to General Electric Company, a corpo-
ration of New York

Application December 21, 1935, Serial No. 55,629

6 Claims. (Cl. 49—2)

My invention relates to incandescent lamp-making machinery generally and more particularly to machines for making the filament supporting structure for so-called tubular incandescent lamps.

The filament supporting structure for tubular incandescent lamps comprises a metal stay rod which may be of channel-shaped cross-section and has a plurality of support wires secured thereto at spaced intervals through the medium of a bead or pellet of vitreous insulating material such as glass. One of the objects of my invention is to provide a machine for manufacturing such a supporting structure.

According to my invention, the machine comprises means for holding a stay rod, preferably in a horizontal position, moving the stay rod intermittently in the direction of its longitudinal axis, fusing vitreous beads or pellets to said stay rod at spaced intervals and then embedding portions of support wires in said vitreous beads or pellets. The machine performs these functions automatically, rapidly and efficiently.

Further features and advantages of my invention will appear from the following detailed description of species thereof and from the drawings.

In the drawings, Figs. 1 and 2 are side and plan views of a machine comprising my invention; Fig. 3 is a side elevation of one pair of stay rod holding jaws; Figs. 4 and 5 are side and plan views respectively of the support wire inserting mechanism; Fig. 6 is a side elevation on an enlarged scale of the end of the support wire inserting slide; and Fig. 7 is a side elevation of a portion of the inserting mechanism part way through its operation cycle.

Referring particularly to Figs. 1 and 2, the stay or support rod 10 is shown mounted in pairs of jaws 11, 12 and 13 at a point mid-way in the manufacturing cycle. Each pair of jaws includes a stationary jaw 14 (Fig. 3) which is mounted on a bar 15, and a movable jaw 16 which is pivotally mounted on a pin 17 in the stationary jaw. The jaws are drawn together to grip the stay 10 by a spring 18 which is hooked around posts in each of the jaws. Between the jaws, the stay is engaged by supports 19 and 20 which are fastened to the bar 15 and by supports 21, 22, 23 and 24 which are attached to a rod 25. The rod 25 extends through the supports 19 and 20 and the stationary jaws 14 and when it is turned by pressure on an arm 26, it lifts the said supports and jaws from the stay 10 so that it may be removed. The rod 25 lifts the mov-

able jaws 16 through levers 27 and pins 28 (Fig. 3). The stay 10 is placed in the jaws so as to butt against an arm 29 extending from bar 15.

As the manufacturing cycle begins, the bar 15 is farther to the right than shown in the drawings and the fires from burners 30 and 31 are directed against a portion of the stay. When the stay becomes heated, a cylindrical pellet or bead 32 of glass or some other insulating material is brought into engagement therewith and is fused thereto. The pellet 32 is located in a well in the end of a holder or plunger 33 which is mounted in a bushing 34 in turret 35 and is moved upward to bring the pellet into contact with the stay. The particular holder or plunger 15 33 carrying the pellet is one of a plurality located in the turret adjacent the periphery and when in position below the stay is located over the end of a rod 36 (Fig. 1). The rod 36 engages a cap nut 37 on the end of the plunger 33 and contracts a spring 38 as the plunger is moved upward. The rod 36 is slidably mounted in a portion of a standard 39 and is moved upward by a lever 40 which is moved by engagement of a roller 41 thereon with a cam 42. The lever 40 pivots on a pin 43 which is supported by a bracket 44 and is moved in one direction by the cam 42 and in the other by a spring (not shown) connected thereto. After the pellet 32 is fused to the stay 10, the plunger 33 is allowed to move down to its former position.

Both the bar 15 and the turret 35 are now indexed, the former to bring another portion of the stay, to which a pellet is to be attached, under the fires and the latter to bring another plunger carrying a pellet 32 into position below the stay. The bar 15 is slidably mounted in ways in standards 45 and 46 in which it is held by plates 47, 48 and 49, 50 and 51 and is locked in position by the engagement of a roller 52 on a rod 53 with notches 54 in the bottom edge of the bar 15. The rod 53 is slidably mounted in the standard 46 and is connected through a link 55 to a lever 56 which is operated by a cam 57. At the start of the indexing movement a high part of the cam 57 is brought under a roller 58 carried by the end of the lever 56, and the roller 52 is withdrawn from the notch 54 in the rod 15. The roller 58 is kept in contact with the cam 57 by a spring 59 extending between the lever 56 and a stationary part of the machine. The indexing is then brought about when a roller 60, which is located in one of the notches 54 of the bar 15, is moved to the left, carrying the bar 15 into a new position. The bar 15 is ad-

vanced a distance equal to the spacings of the notches 54 and is locked in position by the roller 62 which is raised into the particular notch 54 then located above it. The indexing roller 60 5 is mounted on a rod 61 which also extends through arms 62 and 63 and roller 64. The arms 62 and 63 are pivoted on bolts mounted in the end of a lever 65 and are engaged by torsion springs 66 and 67 which keep the roller 60 in engagement 10 with the bar 15. Lever 65 is mounted on a pin 68 in a bracket 69 and engages a cam 10 through a roller 71. When the bar 15 is advanced, a high part of cam 10 engages the roller 71 and the lever 65 moves to the position shown. The roller 15 71 is kept against the cam 10 by a spring 72 which is located between the lever 65 and the standard 46. Having indexed the bar 15, roller 60 is now pulled down out of the notch 54 by an arm 73 and is moved back to the next notch 20 in order that the bar may again be indexed. The arm 73 engages the roller 64 and is mounted on a rod 74 which is moved vertically in a portion of the standard 46 by a lever 75. The lever 75 is connected to the rod 74 through a link 76 and 25 is actuated when a cam segment 77 engages a roller 78 thereon. A spring 79, which extends between lever 75 and a stationary part of the machine, keeps the rod 74 up when the cam segment 77 is not in position.

30 The turret 35 is mounted on a sleeve 80 which surrounds a spindle 81 extending upward from the standard 39 and is attached to a ratchet 82. When the turret is to be indexed to bring a plunger 35 containing a pellet 32 into position below the stay 10, the ratchet 82 is caught by a pawl 83 and turned counter-clockwise. The pawl 83 is mounted on a pin 84 extending from an arm 85 and is held against the ratchet by a spring 86 which extends between posts in the arm and the pawl. The pawl 83 is moved by the arm 85 when a high part of a cam 87 comes below a roller 88 on a lever 89 which is connected to the arm 85 by a rod 90. The lever 89 is mounted on a pin 91 in a bracket 92 and a roller 88 thereon 40 is held against the cam 87 by a spring 93 which extends between said lever and a stationary part of the machine. The turret 35 is held in place when the pawl 83 is returned by the engagement of a ball 94 with one of the notches 95 in the upper surface of the turret 35, said notches being so located that the plungers will be properly aligned with the stay 10. The ball 94 is mounted in a tube 96 which is held by an arm 97 extending from the spindle 81 and is pressed into the notches 95 by a spring 98 which is located between 50 it and a headless set screw 99.

55 After the pellet 32 is fused to the stay 10, the stay 10 is indexed to another position at which the pellet is allowed to cool and when the stay is again indexed, the pellet is passed into the flame from burner 100. The flame is directed against the outwardly extending end of the pellet 32 and when said end is softened, the flame is cut off by a baffle 101 and the end of a support wire is inserted therein. The baffle 101 is mounted 60 on a lever 102 which engages a cam 103 through a roller 104 and which turns about a pin 105 extending from a portion of the standard 45. The roller 104 is kept against the cam 103 by spring 106 attached to said lever.

65 Filament support wires are inserted in turn in each of the insulating pellets 32 attached to the stay 10, preferably by the mechanism shown in detail in Figs. 4, 5, 6 and 7. This mechanism, as 70 shown in Figs. 1 and 2, is mounted below the path

of movement of the stay 10 on standard 45 and is operated through a lever 107 and a box type cam 108. The lever 107 engages a track in the cam 108 through a roller 109 and pivots on a pin 110 in a bracket 111. The lever 107 actuates 5 the entire mechanism through a link 112 and a slide 113, the said slide 113 being slidably mounted in a bracket 114 which is mounted on the standard 45. The wire 115 that is formed into the support wire is threaded as shown in Figs. 4 10 and 6 through a slot in an end of slide 116, below the end of a leaf spring 117, along the side of the slide 116 and through another slot (not shown) in the slide 116 from a spool 118. The spring 117 is fastened to the slide 116 by a pin 15 119 and prevents the wire 115 from backing up as it is forced into the pellet 32. The end of the wire is carried upward into the pellet 32 by an upward movement of the slide 116 which, like slide 113, is slidably mounted in ways in the 20 bracket 114. The movement of slide 113 is transferred to slide 116 through a cam 120 since a pin 121 which extends from slide 113 is then located in the upper sidewardly extending portion of a slot 122 and the cam 120 is turned about a pin 25 123, causing the slide 116 which engages said cam through a pin 124 to be moved. The pin 123 is mounted in a block 125 which is located in ways in the bracket 114 and is fastened to the bracket by a screw 126. The spool 118, as 30 shown in Fig. 1, is fastened to a plate 127 which in turn is fastened to the slide 116 and is carried upward with said slide.

The slide 116 is moved down after the end of the wire 115 has been inserted in the pellet 32 35 and additional wire is pulled from the spool 118 since the end of the wire is held by the said pellet 32. To prevent the spool 118 from over running, a brake is provided consisting of a pulley 128 which is attached to the spool 118, and a string 129 which is wound around the pulley 128 and which is attached to a screw 130 and a spring 131. The downward movement of cam 113 is considerably longer than the former upward movement and, during the latter portion 45 of the downward movement, a knife 132 at the upper end of the mechanism is moved in from one side and a block 133 (Fig. 5) is moved in from the other side, shearing the wire 115. The knife 132 is fastened to a plate 134 which is supported by a lever 135 and a plate 136. The lever 135 is attached to the plate 134 by a pin 137 and is turned about a pin 138 extending from the bracket 114 as the roller 139 thereon passes into the upper offset portion of a cam slot 140 in 50 slide 113. The block 133 is fastened to the plate 136 which is supported through a bracket 141 and a pin 142 by a lever 143, said lever 143 being turned about a pin 144 extending from the bracket 114 as a roller 145 enters the upper offset 55 portion of a cam slot 146 in slide 113. Plate 136 is pressed against the bottom surface of the knife 132 by a block 147 which is backed by a spring 148 and a bolt 149, thereby assuring that the knife 132 will line up correctly with the block 60 133 at all times. The bolt 149 passes through a slot in the plate 136 and is screwed into the plate 134. As the wire is being severed, a cam 150 extending from the plate 134 engages a wire 151 pushing the end 152 thereof into a position 65 adjacent the wire 115. The wire end 152 passes through an arm 153 of a plate 154 which is mounted on the plate 136. The other end of said wire 151 is attached to plate 154 by a screw 155. As the wire end 152 comes into position, a 70

pin 156 (Figs. 4 and 7) is carried against the end of the support wire 115 extending below the wire end 152, bending it sideward around wire end 152. The pin 156 is carried by the end 5 of a lever 157 which is pivotally mounted on a screw 158 on a bracket 159 on plate 134. Said lever 157 is actuated by a link 160 connected thereto. The vertical position of the link 160 is fixed by a pin 161 which extends from the 10 bracket 114 and is engaged by a pin 162 extending from said link 160. The end of the support wire now having been bent sideward is bent upward by the pin 156, forming a hook, as shown in Fig. 7, in which the filament of the completed 15 lamp is held. This movement of the pin 156 is produced by the link 160 which moves upward, turning the lever 157 about the screw 158. The link 160 is connected to one arm of a lever 163, the other arm of which is at this instant engaged 20 by a roller 164 which is mounted through a screw 165 and a plate 166 on the slide 113. The lever 163 is mounted on a pin 167 which is mounted on a bracket 168 on the bracket 114 and is normally kept in the position shown by a spring 25 169 which extends between the link 160 and a screw in the bracket 114. The position of the parts is now as shown in Fig. 7 and all parts are returned to their former positions by a partial upward movement of the slide 113. The 30 hook formed in the end of the support wire 170 is released from the end 152 of the wire 151 when the cam 150 moves back, the wire springing back and the end 152 being pulled back into the arm 153 thereby.

35 The operations necessary for the machine to fuse one pellet 32 of insulating material to the stay 10, to insert one support wire 170 in said pellet and to form the end of said support wire have now been described and the operations are 40 repeated until pellets and support wires have been attached to the stay at regular intervals along its entire length. When the stay has been completed it is unloaded and the bar 15 is pushed back to the right and reloaded. To push the bar 15 back 45 the roller 60 must first be withdrawn from the notches 54 in the bar by manually pulling rod 61 down. The entire machine is driven by the cam shaft 171 which is turned by means not shown.

50 What I claim as new and desire to secure by Letters Patent of the United States is:

1. In a device of the class described, the combination of means for holding a stay rod, means for moving said stay rod intermittently in the 55 direction of its longitudinal axis, a heater disposed adjacent the path of movement of said stay rod for heating said rod, a holder for a vitreous pellet disposed adjacent the path of movement of said stay rod and said heater, means for moving said pellet holder toward the heated portion of said stay rod to fuse said pellet thereto, and support wire feed mechanism located adjacent the path of movement of said stay rod for inserting a portion of a support wire in the softened pellet.

2. In a device of the class described, the combination of means for holding a stay rod, means for moving said stay rod intermittently in the direction of its longitudinal axis, a heater disposed adjacent the path of movement of said stay rod for heating said rod, a holder for a vitreous pellet disposed adjacent the path of movement of said stay rod and said heater, means for moving said pellet holder toward the heated portion 70

of said stay rod to fuse said pellet thereto, another heater disposed adjacent the path of movement of said stay rod at a subsequent rest position for softening said pellet, and support wire feed mechanism also located at said subsequent rest position for inserting a portion of a support wire in said softened pellet. 5

3. In a device of the class described, the combination of means for holding a stay rod, means for moving said stay rod intermittently in the 10 direction of its longitudinal axis, a heater disposed adjacent the path of movement of said stay rod for heating said rod, a holder for a vitreous pellet disposed adjacent the path of movement of said stay rod and said heater, means for moving said pellet holder toward the heated portion of said stay rod to fuse said pellet thereto, support wire feed mechanism located adjacent the path of movement of said stay rod for inserting an end of a support wire in the softened pellet, 20 and means for forming a hook on the other end of said support wire. 15

4. In a device of the class described, the combination of means for holding a stay rod, means for moving said stay rod intermittently in the 25 direction of its longitudinal axis, a heater disposed adjacent the path of movement of said stay rod for heating said rod, holding means for vitreous pellets disposed adjacent the path of movement of said stay rod and said heater and 30 comprising a turret, a plurality of holders for said pellets mounted on said turret, means for indexing said turret in proper time relation to the movements of said stay rod to bring one of said holders adjacent thereto, means for moving said holder toward the heated portion of said stay rod to fuse a pellet thereto, and support wire feed mechanism adjacent the path of movement of said stay rod for inserting a portion of a support wire in the softened pellet. 35

5. In a device of the class described, the combination of means for holding a stay rod in a substantially horizontal position, means for moving said stay rod intermittently in the direction of its longitudinal axis, a heater disposed adjacent the path of movement of said stay rod for heating said rod, holding means for vitreous pellets disposed adjacent and below the path of movement of said stay rod and adjacent said heater, said holding means comprising a horizontally disposed 40 turret, a plurality of vertically disposed holders on said turret for holding said pellets on their upper ends, means for indexing said turret in proper time relation to the movements of said stay rod to bring one of said holders under said stay rod, means for raising said holder toward the heated portion of said stay rod to fuse a pellet thereto, and support wire feed mechanism adjacent the path of movement of said stay rod for inserting a portion of a support wire in the 45 softened pellet. 50

6. In a device of the type described, the combination of a substantially horizontally disposed bar having a plurality of notches at spaced intervals in an edge thereof, means for engaging 55 said notches to intermittently move said bar horizontally, a plurality of pairs of jaws mounted on said bar for holding a stay rod, means disposed adjacent the path of movement of said stay rod for fusing a vitreous pellet thereto, and means also disposed adjacent the path of movement of said stay rod for inserting a portion of a support wire in said pellet. 60

FRANK J. MALLOY.
